CLAIM

The ornamental design for a strap retainer for swim goggles, as shown and described.

DESCRIPTION

FIG. 1 is a front perspective view of a strap retainer for swim goggles showing my new design;

FIG. 2 is a rear perspective view thereof;

FIG. 3 is a front elevation view thereof;

FIG. 4 is a rear elevation view thereof;

FIG. 5 is a left side elevation view thereof, the right side elevation view being a mirror image thereof;

FIG. 6 is a top plan view thereof;

FIG. 7 is a bottom plan view thereof; and,

FIG. 8 is a rear perspective view, similar to FIG. 2, showing the restraining strap of the swim goggles.

The broken lines in the drawings illustrate environment and form no part of the claim.
